(57) **CLAIM**

The ornamental design for an EAS device detacher, as shown and described.

DESCRIPTION

FIG. 1 is a top perspective view of my new design for an EAS device detacher with the detacher in the base.

FIG. 2 is a front view of my new design for an EAS device detacher with the detacher in the base.

FIG. 3 is a back view of my new design for an EAS device detacher with the detacher in the base.

FIG. 4 is a first side view of my new design for an EAS device detacher with the detacher in the base.

FIG. 5 is an opposite side view of my new design for an EAS device detacher with the detacher in the base.

FIG. 6 is a top view of my new design for an EAS device detacher with the detacher in the base.

FIG. 7 is a bottom view of my new design for an EAS device detacher with the detacher in the base.

FIG. 8 is an upper perspective view of my new design for an EAS device detacher with the detacher out of the base and its internal surface turned upward.

FIG. 9 is a bottom view of my new design for an EAS device detacher with the detacher out of the base; and,

FIG. 10 is a top view of my new design for an EAS device detacher with the detacher out of the base.

The broken line showing of screw heads is included for the purpose of illustrating portions of the "article" and forms no part of the claimed design.
